(**) Term: **14 Years**

(57) **CLAIM**

(21) Appl. No.: **29/128,524**

An ornamental design for a handheld electronic article surveillance tag deactivator, as shown and described.

(22) Filed: **Aug. 24, 2000**

DESCRIPTION

(51) LOC (7) Cl. **10-05**

FIG. 1 is a top perspective view showing the new design;

(52) U.S. Cl. **D10/104**

FIG. 2 is a top plan view thereof;

(58) Field of Search D10/104, 106,
D10/116, 121; 340/540, 541, 545, 555,
561, 571, 572, 573, 689

FIG. 3 is a right side elevational view thereof, the left side

being a mirror image thereof;

FIG. 4 is a bottom plan view thereof;

FIG. 5 is a front elevational view thereof; and,

FIG. 6 is a rear elevational view thereof.
